UNITED STATES PATENT OFFICE.

GEORGE THOMAS CRIPPS, OF TORONTO, ONTARIO, CANADA.

EGG-TESTER.

1,073,594.

Specification of Letters Patent. Patented Sept. 23, 1913.

Application filed October 30, 1912. Serial No. 728,553.

To all whom it may concern:

Be it known that I, GEORGE THOMAS CRIPPS, of the city of Toronto, in the county of York, in the Province of Ontario, Canada, have invented certain new and useful improvements in Egg-Testers, of which the following is the specification.

My invention relates to improvements in egg testers, and the object of the invention is to devise a simple device in which the egg is illuminated and reflected in a suitable mirror so that both sides of the egg will be simultaneously under observation and in which the power of the reflector designed to throw the light against the egg is increased and by which the eyes of the operator will be shielded while testing the eggs and it consists essentially of a casing provided with a suitable light at the bottom thereof and having an opening at the top and an opening in the side and a reflecting mirror comprising two leaves connected together at their inner ends and pivoted at the point of connection to the wall of the casing, so that they will alternately cover the top and side openings of the casing as hereinafter more particularly explained.

Figure 1, is a general perspective view of my device showing the egg in position. Fig. 2, is a vertical section through Fig. 1. Fig. 3, is a perspective view of my device as shown when the side opening is employed.

In the drawings like letters of reference indicate corresponding parts in each figure. A is a casing preferably and substantially oval in vertical section and having flat ends A' and A'', the lower end being formed into a stand A³ connected to a base board A⁴. The casing A is also preferably divided horizontally so as to form two halves A⁵ and A⁶, the upper half A⁵ being provided with a slight enlargement A⁷ at the lower edge forming a groove A⁸ into which the upper end of the lower portion A⁶ is inserted.

B is an incandescent light secured in any suitable manner to the base board A⁴ and provided with the usual connections extending through the opening A⁹ in the side of the base A³.

A¹⁰ is an opening in the upper flat end of the casing A and A¹¹ is an opening in the side of the casing in proximity to the top thereof.

C is a double reflector comprising the leaf C' and the leaf C² having inturned lips C³.

The reflector C is pivotally connected at C⁴ to the wall of the casing A directly above the opening A¹¹.

In testing the eggs ordinarily where economy of time is essential I use my tester as shown in Fig. 3, the leaf C² of the reflector being turned upwardly and the opening A¹⁰ covered by the reflecting leaf C'. The rays of the light from the incandescent bulb pass through the opening A¹¹ and the eggs are passed successively by the operator in front of the opening, the upturned leaf C² serving to protect the eyes of the operator by reflecting the upwardly extending rays of the light down.

When it is desired to test the eggs with great care and where economy of time is not essential I use the tester as shown in Figs. 1 and 2. The egg is placed in the hole A¹⁰, the rays of light passing upwardly through the egg, one side of the egg being directly under the observation of the operator and the other side being reflected in the mirror leaf C'. By this means both sides of the egg are simultaneously in view of the operator.

To provide sufficient ventilation in the interior of the casing the lip C³ prevents the mirror leaf C² from entirely closing the opening A¹¹, thereby allowing the heated air to pass between the outside wall of the casing and the leaf C².

D is a tapered reflector provided with corrugations extending from the top to the bottom of the reflector. The reflector D is placed within the casing A, so as to surround the incandescent light B as shown in Fig. 2 of the drawings. By this means a maximum reflecting surface is provided thereby increasing the transparency of the egg subjected to the rays of light from the bulb.

From this description it will be seen that I have devised a very simple device wherein both sides of the egg may be under the observation of the operator and in which a maximum reflecting surface is provided for the light illuminating the egg and in which sufficient ventilation is provided and the eyes of the operator protected during the operation of testing.

What I claim as my invention is:

1. An egg testing device comprising a casing provided with a suitable source of artificial light in the interior thereof and having an opening at the upper end thereof in

- which the egg is designed to rest and an opening in the side, and a reflecting mirror pivotally mounted between said openings as and for the purpose specified.
5. An egg testing device comprising a casing provided with a suitable source of artificial light in the interior thereof and having an opening at the top, and an opening in the side in proximity to the top, and a reflecting mirror comprising two leaves set at an angle one to the other and pivoted to the casing between the opening in the top and the opening in the side at the apex of the angle formed by the two connected leaves to alternately close the openings in the same as and for the purpose specified.
10. An egg testing device comprising a casing provided with a suitable source of arti-
15. ficial light in the interior thereof and having an opening in the side in proximity to the top thereof, and a reflecting shield extending outwardly from the casing over such opening, as and for the purpose specified.
4. An egg testing device comprising a casing provided with a suitable source of artificial light in the interior thereof, and having an opening at the top, and an opening in the side in proximity to the top, and means for simultaneously covering one of said openings and opening the other.

GEORGE THOMAS CRIPPS.
